UNITED STATES PATENT OFFICE.

TOMEY D. ULRICH, OF SHARPSVILLE, INDIANA, ASSIGNOR OF ONE-HALF TO LYDIA M. GERBER, OF ARGENTA, ILLINOIS.

HUMIDIFIER.

Application filed December 24, 1925. Serial No. 77,617.

My invention relates to improvements in devices for cooling or humidifying air, the principal object being to provide a new and improved device of this character in which novel provision is made for moistening air which is induced to flow through a casing, by an electric fan or some equivalent means.

A still further object of the invention is to make provision for supplying cooling air to the fan motor, from the exterior of the humidifying casing, so that said motor will be kept cool and dry and cannot be affected by the moisture of the air within the casing.

With the foregoing and minor objects in view, the invention resides in the novel subject matter hereinafter described and claimed, the description being supplemented by the accompanying drawings.

Figure 1 is a side elevation of a humidifier constructed in accordance with my invention.

Figure 2 is an end elevation.

Figure 3 is an enlarged vertical longitudinal sectional view as indicated by line 3—3 of Fig. 2.

Figure 4 is a vertical transverse section on line 4—4 of Fig. 3.

Figure 5 is a horizontal sectional view as indicated by line 5—5 of Fig. 3.

Figure 6 is a perspective view of a frame structure used to support one of the air moistening, absorbent members.

The form of construction selected for illustration in the present application may be considered as preferred, with the understanding however that within the scope of the invention as claimed, variations may be made.

The numeral 7 designates a vertically disposed casing preferably formed of sheet metal, said casing being closed at its bottom as at 8, being formed with an arched top 9, and having a four-sided wall 10. The lower portion of this wall is formed with air inlet perforations 11 and said lower portion is equipped with a perforated door 12 for giving access to certain interior parts, permitting removal and reinsertion of such parts. The upper portion of the side wall 10 is formed with a relatively large air outlet opening 13 which is preferably surrounded by an outwardly projecting annular flange 14. Directly opposite this opening 13, is a comparatively small opening 15, through the casing wall 10, for a purpose to appear.

Disposed within the confines of the flange

14, is a fan 16 which is detachably connected by a set screw or the like 17 with the shaft of an electric motor 18, the latter being suitably supported in the upper portion of the casing 7. In the construction disclosed, the motor 18 is provided with upstanding ears 19 secured by a bolt 20 to a pair of plates 21 which project vertically downward from the casing top 9. Between these plates, I position the current conducting wires 22 for the motor, said wires being connected with an appropriate rheostat or other form of switch 23. When the fan 16 is driven, it induces entrance of air into the casing through the perforated lower portion thereof and causes discharge of such air through the opening 13, and provision is made for moistening this air. As this humidified air would have an injurious effect upon the motor 18, I do not permit it to pass through the motor casing. Instead, I provide a horizontally disposed air-conducting tube 24 which leads from the opening 15 to the inner end of the motor 18, the inner end of said tube preferably surrounding the motor casing and being notched as at 25 to receive the usual brush holders and adjusters 26.

Within the casing 7, between the air inlet and outlet means, I provide a water trough 27, this trough being preferably formed by extending a horizontal flange 28 inwardly from the casing wall 10, and providing the inner edge of this flange with an upstanding annular flange 29. Another water container, in the form of a pan 30, is provided in the lower portion of the casing 7, the latter preferably having perforated supports 31 for said pan. The supports 31 are preferably in the form of two right angular metal strips arranged across the bottom 8 of the casing 9 and adjacent two opposite sides thereof as shown in cross section in Fig. 3 and in dotted lines in Fig. 5 and one of which is shown in side elevation in Fig. 4, the perforations being in the vertical sides of the supports as shown at 31^a. A reticulate sleeve 32 of absorbent material, passes over the vertical flange 29 and has its upper end extended downwardly into the water trough 27, this upper end of the sleeve being preferably connected to a wire hoop 33. This hoop snugly surrounds the flange 27 and holds the sleeve in place, and if desired, said hoop may be split to permit of its being readily disconnected from the flange 29. The lower end 110

of the sleeve 32 is positioned in the water pan 30 and it will be obvious that the water from this pan and from the trough 27 will keep said sleeve effectively moistened, so that all air passing through it will be thoroughly humidified.

I preferably provide additional air moistening means around the sleeve 32, said means embodying a frame of the construction disclosed most clearly in Fig. 6. This frame is composed of upper and lower hoops 34 connected by stays 35, said hoops and stays being preferably formed of non-corrosive wire. The hoops are bent into the zig-zag formation shown, and a wrapping of stranded material 36, possessing absorbent qualities, is passed around said hoops and extends between them, thus providing a cylindrical absorbent wall. This wall surrounds the sleeve 32 for the greater portion of the latter's height and it is supported by the bottom of the pan 30, so as to be effectively moistened by the water from the latter. The air entering the casing may readily pass through the strands of this absorbent wall and must then pass through the reticulate sleeve 32, before it can be discharged from the casing by the fan 16. In traveling in this manner, the air is advantageously moistened and cooled, so that high efficiency can be obtained from the device.

In order to fill the pan 30, it is simply necessary to open the door 12, and access to the trough 27 may be had either through the opening 13, or by withdrawing the tube 24 and pouring water into said trough, from a suitable container inserted through the opening 15. Whenever the moistening means should be removed from the casing, this is preferably done by disconnecting or detaching a fan guard 37 which is engaged normally with the flange 14, then removing the fan 16 from the motor shaft, inserting one hand through the opening 13 and lifting the sleeve 32 and the moistener 34-35-36, until the latter will clear the pan 30, then removing the latter through the open door 12 and later removing said moistening device through the same opening. The hoop 33 may be disengaged from the flange or wall 29 and withdrawn through the opening 13, with the sleeve 32.

The lower edge of the opening 13 is preferably straight as shown in Fig. 2 and is considerably above the water level of the trough 27, as will be clear from Fig. 3. There is thus no danger of the fan 16 sucking or drawing water directly from this trough, and this is rather important as positioning of the fan in the flange 14, causes it to produce an unusually strong suction through the casing.

When the fan 16 is in motion air is drawn into the lower portion of the casing through

the air inlets 11 and upwardly between the absorbent wrappings 36 and through the reticulate sleeve 32 into the upper portion of the casing from which it is discharged through the outlet opening 13 in a humidified condition. The perforations 31^a in the supports 31 permit the air drawn through the lower perforations 11 of the sides of the casing adjacent to the supports to circulate freely beneath the pan 30 and pass upwardly between the pan and the casing.

Excellent results have been obtained from the details of construction herein disclosed. They are therefore preferably followed, but within the scope of the invention as claimed, numerous variations may be made.

I claim:

1. In a humidifier, a casing adapted to direct a current of air therethrough, said casing having air inlet means in its lower portion and air outlet means in its upper portion, a water trough around the casing wall, a water pan removably supported in the lower portion of the casing and spaced therefrom, a reticulate absorbent sleeve surrounded by said trough and having its upper end turned downwardly into the trough, the lower end of said sleeve being disposed in said pan and means for creating a current of air through the device.

2. In a humidifier, a casing adapted to direct a current of air therethrough, said casing having air inlet means in its lower portion and air outlet means in its upper portion, a water trough around the casing wall, a water pan in the lower portion of said casing and spaced therefrom, supports in the bottom of the casing on which said pan is removably supported, said supports having perforations to permit the passage of air therethrough and beneath the pan, a cylindrical frame disposed in and projecting upwardly above the pan, absorbent material carried by said frame, a reticulate absorbent sleeve surrounded by and suspended from said trough and having its upper end turned downwardly in the trough, the lower portion of said sleeve extending downwardly within said frame and having its lower end disposed in said pan and means for creating a current of air through the device.

3. In a humidifier, a casing adapted to direct a current of air therethrough, said casing having air inlet means in its lower portion and air outlet means in its upper portion, a water trough around the casing wall, a water pan removably supported in the lower portion of the casing and spaced therefrom, a frame disposed in and projecting upwardly above said pan, said frame comprising upper and lower hoops and upright stays connecting them, said hoops being of zig-zag formation, a stranded absorbent wound around and extending between

said hoops, the strands of said absorbent being held against creeping by the zig-zag formation of the hoops, a reticulated absorbent sleeve surrounded by and suspended from 5 said trough and having its upper end turned down into the trough, the lower portion of said sleeve extending downwardly within the stranded absorbent of said frame and having its lower end disposed in said pan, and means 10 for creating a current of air through the device.

4. In a humidifier, a casing adapted to direct a current of air therethrough, said casing having air inlet perforations in the 15 lower portion of its side walls and an air outlet opening in its upper portion, a water trough within said casing, said trough comprising a horizontal flange extending inwardly from the side walls of the casing and

an upstanding flange on the inner edge of 20 said horizontal flange, a water pan removably supported in the lower portion of the casing, said pan being of less diameter than the casing and spaced from the perforated side walls and above the bottom thereof, a 25 perforated door in the lower portion of the casing for access to the interior parts and permitting removal and insertion of said parts, a reticulated absorbent sleeve surrounded by said trough and having its upper 30 end turned downwardly into said trough, the lower end of said sleeve being disposed in said pan, and means for effecting the passage of air through the casing from said air inlet perforations to the air outlet opening. 35

In testimony whereof I have hereunto affixed my signature.

TOMEY D. ULRICH.
